ROTARY INKING MECHANISM

Hobart N. Durham, Manhasset, N. Y., assignor to
The Goss Printing Press Company, Chicago, Ill.,
a corporation of Illinois

Application January 28, 1939, Serial No. 253,244

6 Claims. (Cl. 101—350)

The invention relates to new and useful improvements in inking mechanisms for fast rotary printing presses, and more particularly to such improvements in the actuating means for the vibrator drums of such rotary inking systems.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

Of the drawings:

Fig. 1 is a vertical section through a part of a rotary inking mechanism embodying the invention;

Fig. 2 is an enlarged detail section on line 2—2 of Fig. 1;

Fig. 3 is a detail section on line 3—3 of Fig. 1; and

Fig. 4 is an enlarged detail of the rotary fluid pressure controlling valve.

Objects of the invention are to provide novel, simple, strong and efficient vibrating means for certain of the ink distributing and transferring rollers or drums of a rotary printing press inking system; to avoid the comparatively complicated and power consuming mechanical vibrating mechanisms heretofore generally in use and to substitute novel, simple and direct-acting fluid pressure actuating means; to provide reversible fluid pressure actuating means to vibrate an ink drum and means actuated by the rotating and vibrating shaft for reversing said actuating means; to provide fluid pressure actuation for the vibrator drums or rolls which is operable from or in conjunction with the pressure lubrication system in use on modern rapid rotary presses; to provide novel and efficient particular mechanisms for applying fluid pressure actuation to the vibrator drives of rotary presses. With these and other objects in view, the rotary and vibratable drums or rollers of the inking system have at one end an elongated shaft which extends beyond its bearing in the press frame, a cylinder is fixed to the press frame, the shaft extension passing concentrically therethrough and projecting beyond the outer end of the cylinder. A piston within the cylinder is mounted on the shaft, the piston being fixed against longitudinal movement relatively to the shaft, but at the

piston is permitted, whereby the piston, under the drive of the pressure fluid, moves the rotating shaft to and fro longitudinally so as to impart the desired combined rotational and vibratory, or reciprocatory movement to the inking drum or like member. Valve means are provided for causing a difference in fluid pressure to be alternately created on the opposite sides to the piston, the valve means being reversed at the end of the stroke directly from the reciprocating shaft. It will be understood that the foregoing general description and the following detail description as well are exemplary and explanatory of the invention, but are not restrictive thereof.

In the embodiment of the invention herewith exemplarily illustrated, it is shown applied to a known form of rotary printing press inking mechanism, which comprises a plurality of rotary ink distributing drums and ink transfer rollers located between the ink fountain and the form inking roller, certain of these rotary members, usually the ink drums, being axially reciprocated or vibrated in addition to their rotary movement. These members are usually rotated by gearing driven from the press drive. As here shown, axially vibratable ink drums 1 and 2 have their respective shafts 3 and 4 journaled in the press frame 5. A fountain roller 7 and a doctor roller 6 are also fragmentarily shown. As here embodied the shaft 3 or 4 of the axially vibratable drum is journaled in a bushing 11 mounted in the side frame 5 of the press. (Only one shaft and actuating mechanism will be described.) The bushing at its outer end terminates in an integral, flat circular plate 12, which constitutes part of the fluid pressure actuated vibrating means as later described. The shaft 3 extends for some distance beyond the side frame 5 of the press. Mounted on the press frame concentrically with the shaft 3 is a cylinder 15, the inner end of which is formed by the plate 12 previously referred to. The end 16 of the cylindrical wall sets into and makes a seal joint with an annular shoulder in the plate 12, and terminates in a flange 17 which is fastened to the press frame by screw bolts 18. The outer head 19 of the cylinder is centrally apertured, the shaft 3 projecting through and beyond it, the valve actuating means being connected to the exterior end of the shaft.

Surrounding the shaft 3 on the exterior of the cylinder head 19 is a packing gland 23, and a similar gland 24 surrounds the shaft 3 at the inner end of the bushing 11. The sleeve 11 receives lubricating oil from the cylinder and this

drains out into the general lubricating system through drainage passage 25. Within this cylinder 15 is a piston 28, mounted in fixed axial relation on the shaft 3 while permitting free rotation of the shaft, whereby the pressure alternately applied to the opposite sides of the piston will act to reciprocate or vibrate the rotating shaft. As embodied, within the cylinder, two collars 29 and 30 are mounted in spaced-apart relation on the shaft 3, and are held in fixed position by clamping screws 31 and 32. On the adjacent sides of the collars 29 and 30 are anti-friction bearings 33 and 34, one of the raceways of each bearing being set into the piston 28, 10 the shaft thereby being free to rotate within the piston, but the piston carrying the shaft and drum with it in its reciprocatory movement under the action of the pressure fluid.

So far as concerns certain features of the invention, any form of valve mechanism for reversing the action of the pressure fluid in the cylinder may be employed. As embodied, a rotary valve 41 is mounted in a block 40 which is bolted to the cylinder block. Valve 41 is interposed between the pipe 42, which supplies the pressure fluid, and two conduits 43 and 44, conduit 43 communicating with the outer end of the cylinder 15, and conduit 44 communicating with the inner end of the cylinder, the partial rotation 20 of the valve supplying the pressure fluid alternately at either side of the piston 15. Valve 41 is held longitudinally in place in the block 40 by a collar 39 at one end and a flange 61 at the other end. Rotary valve 41 has an internal longitudinal aperture 38, closed at one end by a screw plug 37. The valve is supplied with a plurality of ports 46 in line with the pipe 42, located to receive the pressure fluid at all angular positions of the valve 41. The valve has also a plurality of ports 48 30 positioned to connect the interior aperture 38 of the valve alternately with the conduits 43 and 44, to supply the pressure fluid alternately to the two ends of the cylinder as described. The means for allowing fluid to flow from the two ends of the cylinder 15 comprise conduits 53 and 54 lying parallel to the intake conduits 43 and 44, the conduits 53 and 54 having exhaust ports 55 and 56 for exhausting the used pressure fluid from the cylinder. In the outer surface 40 of the valve 41 are two elongated ports 57 and 58, port 57 serving to connect the conduit 43 with the conduit 53 of their exhaust stroke and port 58 serving to connect the conduits 44 and 54 on their exhaust stroke.

The embodied means for imparting reciprocatory partial rotation to valve 41 is connected to the ink drum shaft, and is shown in Figs. 1 and 2. At one end of valve 41 is an annular flange 61 which is external to the valve housing. The 50 flange has an arcuate cut-out portion 62 in which is a pin 63, fixed to and projecting from the valve housing, and limits the amplitude of movement of valve 41. Fixed also to the flange 61 and projecting outwardly therefrom is a pin 66, which is 60 within an opening 67 in a lever 68, which lever is pivoted on a pin 69, mounted in the valve housing. A spiral tension spring 68' is connected to a pin 70, fixed on said lever 68, and to a pin 70', fixed in the valve housing, the spring tending to hold the lever 68 at either side of the center of amplitude. On the exterior end of the shaft 3 is a pair of collars 73 and 74 and a pin 75 fixed in the lever 68 projects into the space between the collars. Just as the shaft approaches the 70 end of its travel in one direction, it moves the 75

lever 68, which after passing over the center is snapped by the spring 68', and due to the play in opening 67 moves to the opposite position, and thereby imparts to valve 41 the rotation required to reverse the pressure in the cylinder 15.

In presses employing pressure lubrication, the pipe 42 may be connected to the oil pressure system, and the exhaust ports may return the oil to that system or be led to a bearing to be lubricated. A housing 79 enclosing the entire 10 mechanism is provided.

The invention in its broader aspects is not limited to the specific mechanisms shown and described but departures may be made therefrom within the scope of the accompanying claims 15 without departing from the principles of the invention and without sacrificing its chief advantages.

What I claim is:

1. In a rotary printing press inking mechanism 20 comprising a plurality of cooperating rotary ink distributing and transferring members, one or more of said members being also axially vibratable, a rotary and vibratable inking member having a shaft journalled in the press frame, a piston held against axial movement on said shaft, a cylinder in which the piston reciprocates, reversible valve means for alternately creating a difference in fluid pressure on the opposite sides of said piston and means actuated by said axially 25 moving shaft for reversing said valve means.

2. In a rotary printing press inking mechanism comprising a plurality of cooperating rotary ink distributing and transferring members, one or more of said members being also axially vibratable, a rotary and vibratable inking member having a shaft journalled in the press frame, anti-friction bearings mounted in fixed position on said shaft, a piston mounted in said bearings to move axially with the shaft, there being free 40 relative rotary movement between the piston and shaft, a cylinder in which the piston reciprocates, reversible valve means for alternately creating a difference in fluid pressure on the opposite sides of said piston and means actuated by said axially 45 moving shaft for reversing said valve means.

3. In a rotary printing press inking mechanism comprising a plurality of cooperating rotary ink distributing and transferring members, one or more of said members being also axially vibratable, a rotary and vibratable inking member having a shaft journalled in the press frame, spaced-apart collars fixed to said shaft, thrust bearings between said collars and a piston between said bearings, a cylinder in which the piston reciprocates, reversible valve means for alternately creating a difference in fluid pressure on the opposite sides of said piston and means actuated by said axially moving shaft for reversing 50 said valve means.

4. In a rotary printing press inking mechanism comprising a plurality of cooperating rotary ink distributing and transferring members, one or more of said members being also axially vibratable, a rotary and vibratable inking member having a shaft journalled in and projecting out from the press frame, a cylinder fixed on said frame concentrically with said shaft, a piston in the cylinder mounted in fixed axial relation on the shaft, the piston and shaft being in free rotative 70 relation, reversible valve means for alternately supplying fluid under pressure to and allowing it to flow from the ends of said cylinder and means actuated by said axially moving shaft for reversing 75 said valve means.

5. In a rotary printing press inking mechanism comprising a plurality of cooperating rotary ink distributing and transferring members, one or more of said members being also axially vibratable, a rotary and vibratable inking member having a shaft journalled in and projecting out from the press frame, a cylinder fixed on the exterior side of the press frame concentrically with said shaft, the shaft extending through and projecting beyond the cylinder, a piston in the cylinder mounted in fixed axial relation on the shaft, reversible valve means for alternately supplying fluid under pressure to and allowing it to flow from the ends of said cylinder, and means connected to

said shaft internally to said cylinder and actuated by the axial movement of the shaft for reversing said valve means.

6. In a rotary printing press inking mechanism comprising a plurality of cooperating rotary ink distributing and transferring members, one or more of said members being also axially vibratable, a rotary and vibratable inking member having a shaft journalled in the press frame, reversible fluid pressure actuated means for vibrating said shaft and member, and means actuated by the rotating and vibrating shaft for reversing said fluid pressure actuated means.

HOBART N. DURHAM.
